DESIGN FOR PAPER OR THE LIKE

Thelma Mendsen, New York, N. Y., assignor to Fravessi-Lamont, Inc., New York, N. Y., a corporation of New York

Application February 15, 1945, Serial No. 117,985

Term of patent 7 years

(Cl. D59—2)

To all whom it may concern:

Be it known that I, Thelma Mendsen, a citizen of the United States, residing at New York, in the county of New York and State of New York, have invented a new, original, and ornamental Design for Paper or the like, of which the following is a specification, reference being had to the accompanying drawing, forming part thereof.

The figure is a plan view of a piece of paper or the like, showing my new design.

The dotted lines on the drawing outline the design unit which is repeated in regular succession as indicated by the extensions beyond the unit boundary.

I claim:

The ornamental design for paper or the like, as shown and described.

THELMA MENDSEN.
